UNITED STATES PATENT OFFICE

ARTHUR J. KEISER, OF ROCHESTER, NEW YORK, ASSIGNOR TO THE BIRCHER CO. INC.,
OF ROCHESTER, NEW YORK

STAMP AFFIXING MACHINE

Application filed October 16, 1929. Serial No. 400,133.

The present invention relates to stamp affixing machines and an object of the invention is to provide an affixing element which has a stamp-roll carrying member and a feeding member relatively movable about a common axis to effect the feeding of the stamps one at a time to affixing position. Another object of the invention is to provide an affixing element embodying two rotary drums turning together about a common axis and having relative movement about said axis for effecting a feeding of a strip from a stamp-roll supported by one of the members. Still another object of the invention is to provide for separating the stamps one at a time from a strip of stamps by means of pressure created on the envelopes during the affixing of the stamps to the envelopes. A further object of the invention is to provide a novel means of deflecting a strip of stamps through a feed opening in an affixing element.

To these and other ends, the invention consists of certain parts and combination of parts all of which will be hereinafter described: the novel features being pointed out in the appended claims.

In the drawings:

Fig. 1 is a plan view of a machine embodying the present invention;

Fig. 2 is a front elevation of the same machine;

Fig. 3 is a vertical section on the line 3—3, Fig. 1, parts being broken away;

Fig. 4 is a plan view of the lower casing;

Fig. 5 is a section on the line 5—5, Fig. 1, with parts removed.

Fig. 6 is a fragmentary section showing the stamp strip projected for folding by the folding device;

Fig. 7 is a fragmentary section showing the manner in which the upper rotary element is removably held in position;

Fig. 8 is a plan view of the interior of the machine below the feeding table, parts being broken away;

Fig. 9 is a detail view of the clutch for controlling the upper rotary element of the stamp affixing machine;

Fig. 10 is a detail view of the clutch controlling cam;

Fig. 11 is a fragmentary view showing the manner in which the envelopes are supported in the stacker;

Fig. 12 is a fragmentary view showing the manner in which the envelopes approach the affixing mechanism from the stacker;

Fig. 13 is a fragmentary view showing the manner in which a stamp is affixed to an envelope;

Fig. 14 is a fragmentary view showing the manner in which a stamp is broken from the stamp strip;

Fig. 15 is a perspective view of the upper rotary element of the stamp affixing mechanism;

Fig. 16 is an enlarged axial section through the upper rotary element of the affixing device;

Fig. 17 is a fragmentary section showing the release device for the spring finger;

Fig. 18 is a fragmentary section showing the manner in which the two parts of the upper rotary element are resiliently connected;

Fig. 19 is a fragmentary section showing the manner in which the clutch is held out of clutching relation;

Fig. 20 is another section of the clutch showing the clutch in clutching position;

Fig. 21 is a plan view of the clutch;

Fig. 22 is a detail section showing the manner in which the clutch parts are bolted together; and

Fig. 23 is a detail end view of the clutch controlling cam.

In the illustrated embodiment of the invention 1 indicates a casing which has an open top and bottom, ledges 2 being provided at the rear portion of its upper edge for supporting an upper casing 3 which opens at its bottom to the casing 1. A removable bottom plate 4 closes the bottom of the lower casing.

The open top part of the lower casing is closed by a removable feed table 5 which projects at one end from one side of the lower casing 1, while a portion of the open front wall is closed by a removable front plate 6.

which projects beyond the lower casing to the outer end of the feed table to provide a guide plate. Secured to the feed table on the projecting portion is an inclined rest 7 on which the envelopes to be stamped are stacked, one side of the stack resting against the guide plate 6. Projecting forwardly from the guide plate is a wall or plate 8 with which the forward end of the envelopes in the stack 10 engage, this plate being spaced from the table at its lower edge in order that the envelopes may be fed from the bottom of the stack. For confining the outer edges of the envelopes to the stack, an outer wall or plate 15 is provided which has an inwardly extending portion 10 at its lower edge guided at 11 on the under side of the table 5.

With the end in view of retarding the movement of the envelopes in the stack above 20 the bottom one so as to prevent the feed of more than one envelope at a time, the front plate 8 is cut away at 12 and in front of this cut away portion is arranged a retarder comprising, in this instance, a cylinder 13 which 25 is secured by a screw 14 against turning on a rod 15 which is also held against turning by a set screw 16. This cylinder has two smooth circumferential metal surfaces 17 and an interposed circumferential rubber surface 18 30 which has greater diameter than the metallic surfaces. This rubber surface has a high coefficient of friction and will engage the upper surfaces of the forward ends of the lowermost envelopes due to the fact that the lower 35 most envelopes tend to project in advance of the stack thus holding back all of the lowermost envelopes in the stack except the bottom one which is moved forwardly by the feeding mechanism as will be described. The 40 cylinder 13 while held against turning on the rod 15 may be released from the rod and shifted to present another portion of the rubber surface to effective position when a portion thereof has become worn.

45 It is preferred to mount the retarder so that it will yield to envelopes of different thicknesses and to this end the rod 15 is resiliently supported as by an arm 19 which is mounted to rock on a shaft 20 journalled in a frame 21 mounted to rock on a shaft 22 which is journalled in the lower casing. A spring 23 is interposed between the upper end of this arm and the upper housing and surrounds a rod 24 which projects through the top of the housing and carries an adjusting nut 25 through which the compression of the spring may be varied.

Mechanism for feeding the envelopes from the bottom of the stack one at a time may comprise a pair of rotary members 26 arranged upon the shaft 22 and each having a smooth concentric peripheral portion 27, and a peripheral portion 28 formed of rubber or other material having a high coefficient of friction. A drop 29 is provided at the

70 rear end of each peripheral portion 27. The outer rotary member has its portion 28 bulged at 29^a in rear of the shoulder. The peripheries of the two rotary members co-operate with the two smooth surfaces 17 on the retarder, and when peripheral portions 27 engage the retarder no feeding of envelopes takes place. After these portions pass the lowest envelope, the forward edge 75 of the envelope drops so that the peripheral portions 28 engage the lowest envelope and project it forward against the shoulders formed by the rear ends of the peripheral portions 27 thus properly positioning the envelope for a feeding action by the peripheral portions 28. The bulge 29 on the outer peripheral portion 28 tends to shift the envelope toward the rear guide 6 and align the envelope for travel through the machine.

75 From the feeding mechanism the envelope passes to the stamp affixing mechanism. This mechanism, in this instance, is constructed to feed the envelope during the affixing operation. In this instance, this mechanism embodies two rotary elements cooperating with opposite sides of the envelope. The lower one 30 of these elements is secured to the shaft to turn with the latter, and as said shaft 20 is mounted on the swinging frame 21, the axis of the lower rotary element 30 may move toward and from the axis of the upper rotary element. A spring 31 connected to the lower casing 1 and to the swinging member 20 to hold the lower rotary element toward the upper rotary element the upward movement being limited by an adjustable stop 31^a carried by the frame 21. The turning of the lower rotary element 30 may be effected by a sprocket chain 32 connecting the shaft 22 with the shaft 20. The greater portion of the periphery of the rotary element 30 is cut away at 33 so as not to engage the periphery of the upper rotary element, but the remaining peripheral portion 34 is concentric with the axis of rotation of the rotary element 30 and is unyielding.

100 The upper rotary element or stamp affixing element is supported on a shaft 34^a which is journalled at one end in a bearing 35 in the upper casing 3, its rear end having a collar 36 removably secured thereto by a set screw 37 and abutting a washer 38 on the casing, the washer being pressed toward the collar by a spring 39. Mounted on the shaft is a gear 40 which meshes with a gear 41 secured to the shaft 20 so that the upper rotary element is driven from the shaft 22.

105 With the end in view of turning the upper rotary element or affixing element only when an envelope is passing the stamp affixing means, the gear 40 has a clutch connection with the shaft 34 controlled by the envelopes in passing to the affixing means. In this instance, the gear 40 is mounted to turn relatively to the shaft on a bearing portion 42

and turns between two collars 43 and 44 held against turning on the shaft 34. An opening 45 is provided in the gear 40 and into this opening is adapted to be projected a clutch pin 46 which is movable longitudinally in the collar 44 and is carried by a slide block 47 mounted eccentrically of the shaft to one side of the collar 44, a spring 48 serving to hold the pin 46 normally toward the gear. Movement of the slide block 47 against the action of the spring may be effected by a shifter comprising, in this instance, a cam lever 49 pivoted at 50 within the upper casing and normally held toward the cam face 52 of the slide 47 by the spring 51. To this cam lever 49 is connected one end of a link 53, the other end of the link being connected to an end of an arm 54 on a rock shaft 55 journaled in the lower housing 1. To the rock shaft 55 is secured another arm 56 which extends upwardly through the top plate and has a curved portion 57 which lies in the path of the envelopes as they pass from the stack under the action of the feeding mechanism. This lever is held depressed by an envelope until the envelope has had the stamp affixed thereto when the lever is released causing the cam lever 49 to again swing into the path of the slide block 47 and release the gear 40 from the shaft 34 so that the upper rotary element stops turning with the gear 40.

The upper rotary element of the stamp affixing mechanism comprises, in this instance, two parts, a stamp-roll supporting member 58 and a feeding member turned by the shaft 34^a and having relative movement between them, in this instance, about the axis of turning of the shaft 34^a. In this instance, the stamp-roll supporting member is in the form of a cylinder or drum 58 open at one side having a bearing 59 fitting the shaft 34, the closed side having an eccentric opening 60 in its closed side in which is received a pin 61 projecting from the collar 43. The other feeding member 62 of the rotary affixing element is also in the form of a cylinder or drum with an open side fitted on the periphery of the roll supporting or carrying part 58 and mounted to turn thereon. The two members 58 and 62 are held together with yielding pressure by two pins 63 which are guided in the closed side of the member 58 and project through curved or arcuate slots 64 formed in the side wall of the member 62. Heads 65 on these pins bear on the outer face of the side wall of member 62 on opposite sides of the slots and springs 66 surround the pins within the member 58 and act to hold the heads with yielding pressure against the outer face of the side wall of the member 58.

The inner or stamp-roll supporting member 58 serves as a carrier for the roll of stamps 67 which has a spool 68 fitted to the bearing 59 of the inner member 58 of the upper rotary element. On the inner face

of the member 58 is a guide for the stamps comprising a small frame 69 secured by bolts 70 to the side wall of the member in spaced relation to the inner face of the cylindrical wall. At its receiving end the frame carries 70 at its outer side a finger 71 while its discharge end is arranged adjacent one side of a feeding slot or opening 72 but in spaced relation to said opening. Supported on the inner face of the guide by screws 73^a is a holding finger 73 which is resilient and has its end projecting beyond and cooperates with the adjacent wall of the opening or slot 72 so as to deflect the strip of stamps through the feeding slot. In order to permit the stamps to be inserted in the guide and behind said finger, the guide opens laterally and the spring may be moved away from normal position by a cam 74 on a finger operated shaft 75. That portion of the roll holding member 58 on the opposite side of the slot 72 is deflected inwardly at 76 so as to provide a space 77 for the passage of the strip of stamps between the inner and outer members 58 and 62. 80

The outer or feeding member 62 also has a feed opening 78 in its cylindrical or peripheral portion through which the stamp strip passes and in order to deflect the stamp strip through this feed opening a movable deflecting device is employed. This movable deflecting device is, in this instance, in the form of a lever 79 pivoted at 80 to the outer member 62 to one side of the opening 78 and operating in a slot 81 in the inner member 58. The inner side of the lever 79 has a cam surface 82 adapted to be engaged by pins 83 bridging the slot 81 and serving to force the lever 79 outwardly on the relative turning of the members 58 and 62 in one direction and to permit the lever 79 to move inwardly within the lines of the feeding member 62 on the relative turning of the members 58 and 62 in the other direction. 95

After a stamp has been deflected through the opening 78 it is folded on the outer side of the upper rotary or affixing element. This is accomplished, in this instance, by rotating the upper rotary affixing element of the affixing mechanism past a fixed folding device which, in this instance, comprises the forward edge 84 of a fixed guide 85 which partially surrounds the upper rotary element being pivotally supported at 86 to the upper casing and having its downward movement limited by an adjustable stop 87 carried thereby and co-operating with the upper casing 3. 110

The folded or turned stamp passes under the guide 85 to a moistening device which, in this instance, comprises a moistening receptacle 88 pivotally supported at 89 on the guide plate 6 and carrying an adjustable stop 90 which rests against an abutment 91 on the front plate 8. The receptacle is of L shaped 125

formation so as to provide a portion lying between the retarder 13 and the rotary affixing element of the affixing mechanism and a portion lying to one side of the retarder 13.

5 The portion between the retarder and the affixing mechanism has a wick 92 projecting from the top thereof over which the folded or turned stamp is caused to travel in order to moisten the adhesive on the same. A filling opening 93 may be provided in the receptacle and a spring 94 surrounding the pivot may serve to hold the adjustable stop 90 against the abutment 91.

10 Shortly after the stamp has been moistened it is rolled on an envelope, which at this time is engaged on its under side by the portion 34 of the lower rotary element 30 and pressed upwardly against the moistened stamp. Before the envelope is engaged by 15 the portion 34 it has been fed between the two rotary elements of the stamp affixing mechanism due to the formation of a space because the lower rotary element is cut away.

15 As the stamp is being affixed to the envelope it is separated from the strip. This is effected, in this instance, by breaking the strip at the perforated line to separate the stamp being applied from the strip. The separating or breaking device, in this instance, comprises a breaking lever formed from sheet metal and having a body portion 20 resting against the cylindrical outer surface of the member or part 62 to rock or roll thereon. Two flanges 96 project from opposite sides of the body portion to cooperate with opposite sides of the member 62 in order to prevent sidewise movement of the breaking device. A beveled edge 96^a of this device lies close to and parallel with the adjacent side of the feed opening 78 in the feeding member 62 so that the folder 84 will fold the stamp strip about the edge of the breaking device at the same time that such folder folds the strip about the adjacent 25 edge of the opening 78. Plungers 97 are rockingly supported at 98 on opposite sides of the beveled edge 96^a and project inwardly, being guided loosely in openings in the cylindrical wall of the member 62. Within 30 said member 62 these plungers 97 are surrounded by coil springs 99 which abut against the inner face of the cylindrical wall of the member 62 and also against tension adjusting nuts 100 on said plungers. After 35 the stamp is folded over the breaking device it travels past the moistening device which yields to the breaking device but shortly after the surface 34 on the rotary element 30 is reached, the breaking device begins to 40 rock on the cylindrical surface of the member 62 and about the time the stamp is applied, the beveled edge 96^a has separated from the adjacent edge of the opening 78 causing a breaking of the affixed stamp from 45 the stamp strip, the finger 73 and the bend

in the strip offering sufficient resistance to the slipping of the strip during the breaking operation. After the breaking of the stamp from the strip, the portion 34 and the member 62 continue to engage the envelope and feed the latter forwardly until it is engaged by the final feeding means to be described hereinafter.

50 The feeding of the strip of stamps to present a new stamp is effected by speeding up the rotation of the feeding member 62 with reference to the roll carrying member 53. This occurs before the stamp reaches affixing position, and starts while the stamp to be affixed is travelling under the guide 55 80 which produces sufficient friction on such stamp to hold the strip against movement with reference to the member 68 while it is unrolled from the roll. As a result, the spring holding finger travels backwardly 85 from the opening 78 on a portion of the strip of stamps equal to the width of one stamp and holds this backward position until the moistened stamp is broken from the strip. This speeding up movement of the 90 feeding member 62 is effected, in this instance, by a segment of a gear 101 secured to the lower rotary element 30, the radius of this gear segment being greater than that of the gear 41. The gear segment 101 meshes 95 with a gear segment 102 on the outer member 62 of the upper rotary element.

95 After the stamp has been separated from the strip, the member 62 is retarded in its rotation with reference to the roll carrying member 53 so that the spring finger will push the stamp strip forwardly with reference to the outer member 62 in order to project another stamp through the opening 78 for folding, moistening, affixing, and breaking. The 100 retarding of the feeding member 62 is effected, in this instance, through a gearing comprising a pinion 103 meshing with the gear 40 and having a pinion 104 turning therewith and meshing with the segmental gear 105 on the outer member 62. This segmental gear is engaged during the period that the upper rotary element of the affixing mechanism is travelling from the stamp breaking position to the strip folding position and is at all other times not functioning.

105 The upper rotary element or affixing element of the stamp affixing mechanism is readily removable for refilling and to this end it is removably held on its shaft 34 by a detachable plate 106 which carries a manually operable spring pressed plunger 107 adapted to engage in an annular groove 108 in the shaft 34.

110 From the stamp affixing mechanism, the stamped envelopes are fed to a feeding mechanism which carries the envelopes from the machine. This feeding mechanism takes hold of an envelope before it is released by the stamp affixing mechanism and comprises,

in this instance, a lower roller 109 secured to a shaft 110 which is driven by a sprocket chain 111 from the shaft 20. Above the roller 109 is a roller 112 which through springs 113 is held yieldingly toward the roller.

A handle 115 is connected to the shaft 22 for operating the machine and is constructed so that the shaft may turn only in one direction. The connection, in this instance, comprises a sleeve 116 on the handle 115 which is mounted on the end of the shaft 22 and has an enlargement 117 for a spring 118. The end wall of the enlargement serves as an abutment for one end of the spring and the head 119 of a bolt 120 serves as an abutment for the other end so that the sleeve is urged away from the headed bolt. A pin 121 limits the lateral movement of the sleeve and holds the spring under compression. The end of the sleeve abutting this pin 121 has a notch and a helical cam surface formed from its lowest point to its highest point so that when the handle is turned to move the wall of the notch away from the pin said pin rides up the helical cam and over the notch but when the handle is turned in the opposite direction the notch engages the pin and turns the shaft 22 which by means of the chain drive 32 drives the shaft 20.

30. What I claim as my invention and desire to secure by Letters Patent is:

1. In a stamp affixing machine, the combination with a rotatably mounted stamp-roll carrying member, of a feeding member 35 and rotatable relatively to the roll carrying member about the axis of rotation of the roll carrying member to produce the feeding action.

2. In a stamp affixing machine, the combination with a rotatably mounted stamp-roll carrying member, of a feeding member mounted to turn on and relatively to the roll carrying member about the axis of rotation of the roll carrying member, to produce the 45 feeding action.

3. In a stamp affixing machine, the combination with a rotatably mounted stamp-roll carrying member, of a feeding member surrounding the stamp-roll carrying member and having a cylindrical periphery provided with a feeding opening through which the stamps are fed, said feeding member being mounted to rotate about the axis of rotation of the roll carrying member relatively to the latter to effect the feeding action.

4. A stamp affixing machine, comprising a stamp-roll carrying member, and a feeding member rotatable about a common axis and having relative movement about said axis 60 to produce the feeding action.

5. In a stamp affixing machine, the combination with a stamp-roll carrying member, and a stamp feeding member rotatable together about a common axis and also relatively 65 movable about said axis to produce the feed-

ing action, of means for effecting such relative movement during the turning of the members together about the axis.

6. In a stamp affixing machine, the combination with a stamp-roll carrying member, 70 and a stamp feeding member rotatable together about a common axis and also relatively movable about said axis to produce the feeding action, of means for effecting such relative movement during the turning of the members together about the axis, comprising two mechanisms, one speeding up the rotation of the feeding member ahead of the roll carrying member, and the other slowing down the rotation of the feeding member 75 with reference to the roll carrying member.

7. A stamp affixing machine comprising a rotary stamp-roll carrying drum, and a feeding drum surrounding the stamp-roll carrying drum mounted to turn on the stamp-roll carrying drum about the axis of rotation of the roll carrying drum relatively to the latter to produce a feeding of stamps from the drum, having a cylindrical periphery and a feeding opening in the periphery. 85

8. In a stamp affixing machine, the combination with a stamp-roll carrying member, and a feeding member rotatable together about a common axis and having relative movement about said axis to produce the feeding action, of two segmental gears carried by the feeding member, and means cooperating with said gears during the rotation of the two members together to first advance the feeding member ahead of the roll carrying 95 member and then to retard the movement of the feeding member.

9. In a stamp affixing machine the combination with a rotary stamp-roll carrying drum, of a feeding drum supported by and surrounding the stamp-roll carrying drum and having a feed opening, said feeding drum being mounted to turn on the roll carrying drum about the axis of turning of the roll carrying drum, and means for effecting a 100 turning of the feeding drum in opposite directions on the roll carrying drum during the rotation of the roll carrying drum.

10. In a stamp affixing machine, the combination with a stamp-roll carrying means, 105 a rotary drum enclosing said roll carrying means and having a periphery provided with a feeding opening, and a movable deflector arranged to operate in said feeding opening to deflect a stamp to project it through the feeding opening.

11. In a stamp affixing machine, the combination with a stamp-roll carrying drum, of a feeding drum surrounding the stamp-roll carrying drum, and provided with a feed opening, the drums being mounted for relative turning movement, to effect the feeding action, and a movable stamp deflector pivoted to one side of the feeding opening in the feeding drum, and projecting into said opening, 125 130

and means on the roll carrying drum for effecting the movement of the deflector on the relative movement between the drums.

12. In a stamp affixing machine, the combination with a rotary drum having a feed opening in its periphery, and roll supporting means arranged in the drum of a movable stamp deflector arranged to operate in the feed opening to deflect the stamp strip through said opening, and means operating on the feeding of the strip for projecting the deflector through the opening.

13. In a stamp affixing machine, the combination with a rotary stamp roll carrying drum having a feed opening, of a feeding drum surrounding the rotary roll carrying drum and mounted to turn in opposite directions relatively to the roll carrying drum about the axis of rotation of the roll carrying drum, said feeding drum having a feed opening, and a yielding finger carried by the roll carrying drum and engaging with the wall of the feed opening of the roll carrying drum to hold the stamp strip toward said opening.

14. In a stamp affixing machine, the combination with a rotatable stamp-roll carrying drum provided with a feed opening, of a feeding drum surrounding the roll carrying drum and mounted to turn thereon about the axis of rotation of the roll carrying drum, said feeding drum having a feed opening, a movable deflector pivoted to one side of the feed opening of the feeding drum, and means carried by the roll carrying drum to effect the movement of the deflector through the feed opening of the feed drum on the relative movement between the drums in one direction.

15. In a stamp affixing machine, the combination with a rotary stamp-roll carrying drum having a feed opening in its periphery, of a feeding drum surrounding the stamp-roll carrying drum and having a feed opening in its periphery, said drums being relatively movable to effect a feed of the stamp strip through both feed openings.

16. In a stamp affixing machine, the combination with a drum having a feed opening, a stamp-roll supporting means arranged in said drum, a stamp breaker mounted to one side of feed opening with an edge parallel with an edge of the feed opening, means for folding the strip to cause a portion thereof to overlie the stamp breaker, and means for operating the stamp breaker to cause its edge to move outwardly away from the edge of the feed opening.

17. In a stamp affixing machine, the combination with a rotary drum having a periphery for engaging one face of an envelope provided with a feeding opening, and means for supporting a roll of stamps in said drum for passage one at a time through the feed opening, of a folding means for folding a portion of the strip on the outer side of the

drum during the rotation of the latter, means for separating the folded portion of the strip from the strip, and means cooperating with the face of an envelope opposite the face engaged by the drum to produce pressure on the separating device in order to operate the latter to separate the stamp from the envelope.

18. In a stamp affixing machine, the combination with an envelope engaging element having a feed opening, and means for folding a stamp from a strip passed through the feed opening on the outer face of said envelope engaging element, of a separating device for separating the folded portion from the strip, and means cooperating with the opposite face of the envelope to create pressure thereon to actuate the separating device in order to separate the folded portion from the strip.

19. In a stamp affixing machine, the combination with two elements between which the envelopes are subjected to pressure from opposite sides, one of said elements having means for feeding stamps one at a time to the envelopes subjected to pressure, of a separating device for separating stamps from the strip one at a time, operated by the pressure between the two elements.

20. In a stamp affixing machine, an affixing mechanism comprising a rotary element with which the envelopes engage, said element having means for feeding a strip of stamps one at a time to a feeding point, of a separating device carried by said stamp carrying element and engaging the envelope to separate a stamp from the strip as the stamp is applied to the envelope.

21. In a stamp affixing machine, an affixing mechanism comprising an affixing element having a feed opening and a breaker having an edge parallel with the side edge of the feed opening and a portion engaged by an envelope when a stamp is applied thereto, means for feeding a strip of stamps one at a time through the feed opening and over the breaker.

ARTHUR J. KEISER.
